COMBINATION KITCHEN TOOL

Frank Marino, San Diego, Calif.

Application June 19, 1953, Serial No. 25,575

Term of patent 3½ years

(Cl. D22—3)

To all whom it may concern:

Be it known that I, Frank Marino, a citizen of the United States, residing at San Diego, in the county of San Diego and State of California, have invented a new, original, and ornamental Design for a Combination Kitchen Tool, of which the following is a specification, reference being had to the accompanying drawing, forming part thereof, and wherein:

I claim:

The ornamental design for a combination kitchen tool, as shown.
